Attorney

UNITED STATES PATENT OFFICE.

FRED SACKMANN, OF FALLOON, MONTANA.

MUSICAL INSTRUMENT.

Application filed June 9, 1922. Serial No. 567,099.

To all whom it may concern:

Be it known that FRED SACKMANN, a citizen of the United States of America, residing at Fallon, in the county of Prairie and State of Montana, has invented new and useful Improvements in Musical Instruments, of which the following is a specification.

The object of the invention is to provide a simple and efficient means for mechanically operating or playing an instrument of the stringed type of which a preferred embodiment is shown in the accompanying drawings, wherein:

15 Figure 1 is a plan view, and

Figure 2 is a sectional view parallel with the strings of an instrument equipped with playing means constructed in accordance with the invention.

20 Figure 3 is a transverse sectional view of the same.

Figure 4 is a detail view of one of the operating units.

25 Figure 5 is a detail view of an operating unit, showing the picks upon one side of the operating unit.

The device is shown in the drawing as applied to an instrument of the type as indicated at 10 and includes a keyboard 11 upon which are mounted depressible keys 12 arranged in series or banks, and sound disks 13 axially mounted upon a suitable spindle 14 and provided with lateral picks 15^a adapted for contact successively with the strings 16 between which the disks operate. The picks are preferably of conical tapered form as indicated and may be of relatively soft suitable material having the requisite strength and resistance while affording a relatively smooth or soft contact with the strings which in the ordinary practice are wire. As indicated each disk may be provided with oppositely projecting picks when two strings are to be sounded in unison, as indicated in Figure 5.

The disks are adapted for respective actuation by the keys or buttons 12 and to that end are provided with peripheral ratchet teeth 16 arranged in the path of

operation of a yielding tongue 17 having a 50 terminal dog for successive engagement with the ratchet teeth, and the tongues of the several keys may be carried directly thereby as shown at 18 or may be connected therewith by intermediate rocking levers 19 or 55 the equivalent thereof, according to the relative positions of the keys and disks. Also to prevent backward rotation of the disks retaining pawls 20 may be arranged in engagement therewith.

In operation as will be obvious the pressure of a key or button causes a forward step movement of the related disk to bring one of the picks thereof into engaging relation with the corresponding string which is thereby 65 strained and then released to vibrate the same very much after the manner of operation manually or through the direct agency of the fingers of the operator or of a manually operated pick, with the advantage of 70 increased accuracy in the selection of the strings to be sounded and a uniform straining of the strings in the sounding thereof.

In Figure 5, the operating unit disclosed is provided with picks 15 upon one side only 75 of the disk 13. This operating unit is adapted for use on an instrument of the stringed type where only single strings are located between the disks.

Having described the invention, what is 80 claimed as new and useful is:—

A musical instrument comprising a sounding board, strings disposed over the board, a keyboard located over the strings and mounted upon the sounding board, disks 85 journaled for rotation under the keyboard and provided with ratchet teeth, the lower portions of the disks being disposed transversely with relation to the strings, picks carried by the disk and adapted to engage 90 the strings, there being a pick located adjacent each of the ratchet teeth, spring-supported keys carried by the keyboard, and yieldable tongues connected with the keys and adapted to engage the ratchet teeth. 95

In testimony whereof he affixes his signature.

FRED SACKMANN.
